UNITED STATES PATENT OFFICE.

JOHN J. BORDMAN, OF BROOKLYN, NEW YORK, ASSIGNOR, BY MESNE ASSIGNMENTS, TO MARVIN C. STONE, OF WASHINGTON, DISTRICT OF COLUMBIA.

MACHINE FOR FORMING PAPER CONES.

SPECIFICATION forming part of Letters Patent No. 549,474, dated November 5, 1895.

Application filed July 10, 1889. Serial No. 317,100. (No model.)

To all whom it may concern:

Be it known that I, JOHN J. BORDMAN, a citizen of the United States, residing at Brooklyn, in the county of Kings and State of New York, have invented certain new and useful Improvements in Machines for Forming Paper Cones, of which the following is a specification, reference being had therein to the accompanying drawings.

10 Figure 1 is a side elevation of my paper-cone-forming machine. Fig. 2 is an elevation from the opposite side. Fig. 3 is a top plan view. Fig. 4 is a central vertical section. Fig. 5 is an elevation from the outer end. Fig. 6 is 15 a view, partly in elevation, partly in section, through the center of the revolving carrier. Fig. 7 is a section of the blank-holder, the mandrel, and the pressure devices. Figs. 8 and 9 are views of the two faces of one of the cam-wheels. Fig. 10 is a perspective of one of the stops. Fig. 11 shows the mandrel detached. Fig. 12 shows three cross-sections of the mandrel for fullsize. Figs. 13 and 14 are side views of the operative end of the mandrel. Fig. 15 20 shows a spring friction-washer. Fig. 16 is a perspective of another cam. Fig. 17 is a section of the air-chamber and valve devices. Fig. 18 is a face view of the paper blank. Fig. 19 is a longitudinal section of the paper cone. Fig. 20 is a longitudinal section of the cone, 25 showing a coiled wire inserted. Fig. 21 shows detached the spring-catch which holds the cone-carrier from revolving, and also the device which intermittently releases said catch. Fig. 22 is a plan view of the devices for discharging the cones from the carrier. Fig. 23 shows the former and the adjacent parts in their first position. Fig. 24 shows them just as the paper cone is being taken off.

30 The initial power-shaft is indicated by A, it being provided with a fastened band-wheel A' and a loose wheel A², and being mounted in suitable bearings a a'.

A³ represents the bed-plate of the machine, 35 which may be of any suitable character, and from which rise standards for supporting the operative parts.

Shaft A has a pinion a² for transmitting power to the second shaft B through a gear-

wheel b secured thereto. The shaft B is 50 mounted in bearings in the standards B³ and at B', the latter bearing B' being carried by a collar B², supported on a shaft rising from a standard B⁴. The shaft B carries, among other things, a wheel b', which is feathered to 55 the shaft so that it can play slightly therein longitudinally. It is held in frictional contact with a bevel-toothed wheel b², pressure being exerted by means of a spring b³ bearing against a collar b⁴. The wheel b² engages 60 with the bevel-wheel C³ on a hollow shaft C'. The operation and the mutual relations of these parts will be more fully described hereinafter. At present it will be noted that the revolving cone-carrier C is intermittently 65 stopped and prevented from rotating for intervals by means of a catch-bar D, having a catch d', normally pushed upward by means of a spring d, the bar D being fitted and sliding in a guide D'. The catch d' engages with 70 notches c in the carrier C. The rod D is provided with a lug d³ at the lower end, with which a cam d² on collar B⁴ on shaft B engages. When the cam comes around, it engages with lug d³ and for an instant pulls and holds down 75 the catch d', whereupon the friction between the parts b' and b² is efficient in causing the rotation of the wheels b² and C³, and the carrier C; but when the cam d² disengages from lug d³ the catch d' takes into the next notch 80 c, and the carrier C is again held stationary for an interval.

On the shaft B there is a wheel E on a loose sleeve or hub, (see Fig. 4,) having a cam E', through which the motion is given to several 85 of the parts as follows: Cam E' bears against an arm E², having an antifriction-roller e, this arm being secured to a sliding bar E³, mounted in guide at e'. Bar E³ is pivoted to a lever F at e², and the lever is in turn pivoted to the standard B³ at f. At the upper end the lever F is pivoted by means of a short arm at f' to another sliding bar G, held in guides g g'. A weight at F², secured to an arm f⁴, tends to swing lever F outward around 90 the pivot f—that is, to hold the arm E² and the roller e against cam E'—and insures a movement the reverse of that caused by the cam. 95

Lever F has at the top a cam-like projection F', for a purpose to be described. The bar g³ is secured to bar G and extends to the central vertical plane of the machine, where it is provided with a sleeve g⁴, which is secured to the cone-forming mandrel H H'. There is a spring g² around the sliding bar G, bearing against the guide g' and the bar g³. When the lever F is moved forward by the cam E' 10 the mandrel is caused to slide forward. The spring g² assists in keeping the parts in proper relation to each other.

The part H of the mandrel is a cylindrical bar adapted to both slide and to be intermittently rotated. The part H' is the frustum of a cone. These parts are solid, except that they have a groove h' h² extending in from the peripheral surface. The end of the paper is received therein when it is to be wrapped, 15 it first entering at h', which is made wide to insure an entrance. In the groove there is a swinging or vibratable gripping-finger h³, actuated by spring h⁵. I have shown a form, which for some reasons I prefer, wherein a 20 swinging finger and the spring are integral, being secured in place at h'; but it will be readily understood that the spring and the finger may be separate parts if desired.

The mandrel and cone-former move longitudinally with the parts above described—to wit, those at E², E³, F', and G.

The parts which intermittently rotate the forming-mandrel are the following: J is a wheel loosely mounted on the shaft B, it having a sleeve j. It has, however, a constant tendency to rotate with the shaft B, because of the presence of spring-washers j³ interposed between the wheels b and J, (see Figs. 2, 11, and 15,) those shown being wooden 35 blocks j⁴, pressed against the wheel J by means of spring-plates j⁵, both held in place by screws j⁶. This tendency to rotate is overcome during proper intervals by means of a catch j², adapted to engage with a bar k, 40 which bar is held in the path of the catch by a cam K on wheel E. As soon as the cam turns away from the bar k, a spring k' slides the bar out from the path of catch j², whereupon the friction between wheels b and J is 45 efficient to cause the rotation of wheel J. The catch j² is carried by an adjustable hub J', fastened by screw j' around the sleeve j. The wheel J engages with a wheel J² on sleeve J³ around the shank part H of the forming-mandrel, the latter being connected to the sleeve J³ by feather and groove, so that the mandrel can slide and be at the same time rotated, or slide when the wheel is not rotating. It 55 will be seen that the forming-mandrel can thus be given two motions, either simultaneously or independently. The mandrel is mounted in the laterally-extended bearing B⁵ at the upper end of standard B³.

I will now describe the devices by means of 60 which the paper is fed to the mandrel.

L is a shaft mounted in a bearing at l and having a wheel L', driven by wheel b, and a

wheel L², which engages with a wheel M' on shaft M in a bearing m. The shaft M has a wheel m², which engages with the aforesaid 70 wheel E. The latter is carried by the aforesaid sleeve or hub of wheel E, which at the other end is secured to a cam-wheel N, the periphery of which is throughout a greater portion thereof circular, but which is cut away 75 at n. This acts to alternately lift and hold up on the one hand and on the other allow to drop a rod O, which is secured to a valve O⁵. This valve is mounted in a tube O⁶, having an inlet O³. The tube O⁶ communicates with a chamber O' and has an exit duct O⁴, adapted to be connected with an air-pump. The rod O is mounted in bearings at o². The cam-wheel N engages with this rod through an arm o, adjustably fastened by a collar and 80 set-screw at o'. A hose or other pipe O² extends from the inlet o³ to a pipe O³, which is secured to a rocking arm S. The pipe O³ at the bottom has an expanded plate or sucker O⁷, (see Figs. 3 and 7,) and when an exhaust 85 is applied to the chamber O' there will be suction caused through plate or sucker O⁷, tube O³, hose O², inlet o³, and outlet O⁴—that is to say, this will occur if the valve O⁵ be in such position that its port registers with the inlet o³. 90

The machine, as shown, is provided with parts which supply blanks previously cut; but I do not limit all of the parts of the machine to the specific means for supplying the 100 blanks, as at this date numerous devices are known for accomplishing this.

I have shown a holder P adapted to receive several hundred blanks cut into the proper shape, the shape of this holder 105 conforming approximately to that of the blanks. These rest upon a movable bottom P', against which pushes a rod P², held in a guide p⁴. The rod P² is pushed upward by means of a cord p' passing over pulleys p p³, and having 110 a weight p⁵ attached to it. These devices insure that the top blank of the series shall always be held in contact with the bottom of the sucker or suction-plate O⁷. The holder P is placed by the side of the mandrel H H', 115 one end thereof being more or less nearly parallel to the axis of the mandrel. The side wall is cut away a little at P⁶, so as to form a throat or passage for the blanks. The sucker or suction-plate O⁷ is intermittently vibrated 120 toward and from the mandrel, it being carried by the pipe O⁸, which is secured to a rocking arm S. The latter is pivoted to a lever S', which by a link S² is connected to a slide S³, mounted in a guide s. 125

S⁴ is a link connecting the slide S³ with a vibrating lever S⁵, pivoted in an upright S⁶.

s' s² are projections extending down into the path of the above-described extension F' on lever F. As this lever F oscillates, it 130 alternately strikes these projections, and through these series of levers, links, and slides from S⁵ to S moves the suction-plate o⁷ first away from the mandrel toward the end of the

blank-holder and then back toward the mandrel. At the instant that the suction-plate reaches its outermost position an exhausting of the air from the hose o^2 and tube o^3 is caused by the means above described, and therefore the top blank of the pile is sucked and held against the plate o^7 , and this suction continues while the suction plate and pipe o^8 are moving through their return-
10 throw toward the mandrel. The plate therefore in coming back slides the top blank through the throat at the inner edge of holder. At this time the mandrel is moving outward away from the part C and is not
15 rotating, and the end of the blank is pushed into the enlarged part h' as it moves past the throat P^5 of holder P; and the mandrel, continuing to slide backward the end of the blank, is crowded into the narrow part h^2 of
20 the groove, where it is firmly clamped by the spring-finger h^3 . At the instant the blank is properly seated in the groove the suction is stopped and the operation of wrapping begins.
25 Any preferred material can be used for causing the blanks to retain their conical form after wrapping—that is to say, use may be made of any suitable adhesive substance for causing one fold or layer of paper to ad-
30 here to the next. Paste of suitable kind may be applied to the edges or over the whole surface.

For making the larger and heavier cones, such as are adapted for holders for cigars, I prefer to employ a strong binding or adhesive material, such as the substances which require heating in order to soften them. In applying an adhesive substance of this sort I put it upon the paper while it is still in sheet
35 form and cut the blanks afterward, as this is the more economical plan. If the adhesion be one of the sort requiring heat to cause it to act I employ devices as follows, in conjunction with those above described:

40 T is a pressure-plate situated opposite to the throat of the blank-holder P and opposite to the conical former or mandrel when in position of wrapping. This plate normally tends to move with a yielding pressure toward the mandrel, so that the paper, while being wrapped by the mandrel, will be tightly gripped on the outside. It is pivoted at t^4 , and is pressed forward by weight
45 t and lever $t^1 t^2$, pivoted at t^3 , there being a stop at t^5 to limit the movement.

This pressure-plate or its equivalent is used in all cases—that is to say, I prefer to apply a pressure to the paper as it is being wrapped for the purpose of smoothing down the folds
50 one upon the other and packing them tightly in place and causing the adhesive substance to get firm hold. When heat is to be utilized, as aforesaid, I form a chamber immediately back of this pressure-plate, preferably by side walls T' T', a top T ^{2} , and a rear wall T ^{3} . Inside of this chamber or below it there is situated a heat-generator, such as a gas-

burner, or burner adapted to hold a wick or one capable of vaporizing a light oil. The letter U indicates the same, u representing a part of the supply-pipe.

In operation, the pressure-plate is highly heated and as the blanks are successively wrapped upon the former the side having the adhesive material is softened and under the pressure is caused to enter the pores of the paper and produce a firm fastening of one fold upon another. After the cones are formed upon the mandrel, the latter advances toward the part C, which is formed with conical apertures or sockets c', whose walls conform to the peripheries of the cones. The paper cone is thrust by the mandrel snugly into one of the said apertures or sockets and immediately thereafter the mandrel slides back to the position for beginning another operation, leaving the paper cone in the socket in the part C. Before the mandrel returns with the next cone the part C has been released for an instant and advanced one step, so that an empty socket is presented. To insure that the cone shall be left in the socket and not drawn back by the mandrel I combine with the above-described parts supplemental devices to assist in taking the cone from the mandrel, they consisting of a plate or block I, having a concave upper surface, a rod i carrying said part I and fitting in a guide i', and a spring i ^{2} , which tends to push the part I upward toward the mandrel. This plate or block I engages with the larger end of the cone, it preferably slipping behind the edge of said larger end just as it reaches its position in the socket c'. Then when the mandrel recedes it is ordinarily impossible for the cone to come back, but is forced from the mandrel, the latter slipping from the interior.

By retaining the cones in a device of the nature of that at C they are kept under pressure at a number of points on their periphery or around the whole of it for a period of time after the final wrap has been finished, and the paste, gum, or other adhesive substance is allowed time to set and harden. Instead of this the cone may be discharged loose at once from the mandrel into a suitable receptacle.

When a temporary holder is used, I combine with it a suitable mechanism for finally releasing and throwing out the cones. As shown, this consists of a push-rod R, mounted in a sleeve-guide R', slotted at r. The rod R is intermittently reciprocated on lines radial to the carrier C by means of a link R ^{2} , pivoted to it at r', the pivot sliding in the slot r, and the link R ^{2} is pivotally connected to the crank R ^{3} on a rock-shaft R ^{4} , mounted in a bearing at r ^{2} . At the lower end shaft R ^{4} has a crank R ^{5} , pivoted to the link R ^{6} , which is also pivoted to the arm r ^{3} , secured to the above-described sliding power-rod E ^{3} . When rod E ^{3} is moving toward the carrier C, it, through link R ^{6} and crank R ^{5} , rocks shaft R ^{4} ,

and the latter, through crank R^3 and link R^2 , causes the push-rod R to slide in the guide R' ; and this guide and push rod are so arranged in relation to the carrier C that when 5 the rod R is to operate on a cone it lies opposite to and in line with one of the holders c' , so that the rod on entering the inner end of one of the holding-cavities strikes against the small end of the cone of paper and pushes 10 it outward.

With the devices above described I can combine means for applying a spirally-bent wire to the interior of the paper cones and fastening the wires therein. This is done in 15 manufacturing some sorts of holders for cigars, although it is an operation that may be omitted in making holders of other kinds.

I do not herein claim my improved mechanism for performing the operation requisite 20 to insert the wire, and therefore do not describe the same herein, being about to file a separate application for that subject-matter.

I am aware of the fact that paper-wrapping machines have been used in each of 25 which there was a forming-mandrel and a pull-off mechanism, the latter being generally of the form of a ring and supported stationarily around the former at a place inside of the end of the paper cone or tube, the mandrel being adapted to move from its first position, or the position of wrapping, backward 30 toward and past the pull-off. In my case the pull-off I is normally situated at or outside of the small free end of the mandrel, 35 said mandrel and pull-off being arranged and related in such way that one can move toward the other until the pull-off is situated behind the large end of the paper tube or cone. An arrangement of this sort makes it 40 possible to deliver the paper cones one after another to a receptacle having a receiving chamber or chambers.

I herein refer to the fact that after the blanks have been wrapped on the conical 45 mandrel, and after the heated or softened adhesive has been applied to them, they are subjected to external pressure while being supported on or in an intermittently-moving carrier. For the application of such external pressure I do not limit myself to the 50 exact devices shown—namely, the conical walls of the chambers c' in the carrier C , though for some purposes I prefer such walls, as they can be caused to hold the layers of paper together until the adhesive is cooled or hardened.

I am also aware of the fact that in the manufacture of long paper tubes use has 55 been made of mandrels supported at both ends, said mandrels being mounted above vats or vessels containing bituminous materials and heaters to melt or soften the same, and I do not claim such devices as of my invention; but I believe myself to be the first 60 to have so arranged the parts that the paper cone can be automatically formed and have heat applied to the adhesive therefor, while

the mandrel is revolving in proximity to a non-revolving pressure-plate, and then have the mandrel carry the cone to an automatically-acting pull-off, which causes the removal 70 of the cone from or over the free end of the former.

By having a spring gripping-finger arranged in the way described and shown it co-acts advantageously with the yielding pressure-plate in holding the paper properly during the wrapping, and when the pull-off is engaged with the cone this gripping-finger allows the gripped part of the papers to escape 80 easily.

At this date some cone-making machines are known in each of which the mandrel is moved longitudinally relatively to the pull-off or ejector, as at I , and in others the pull-off has been given a longitudinal movement relatively to the mandrel, and hence all of the features of the present invention are not limited to the exact details shown, inasmuch 85 as a mandrel having features similar to that 90 herein can be used with a modified form of pull-off. Again, in some of said machines provision was made for applying both a coating of wax, and also more or less paste, and when I herein refer to adhesive material and 95 means for heating the same I include such machines as coming within the scope of my invention.

What I claim is—

1. In a machine for making paper cones, an 100 intermittently revolving circular cone carrier having a series of holders adapted to retain the cones under pressure and an intermittently-acting ejector arranged within the cone carrier and adapted to engage positively with 105 and bear against the cones to remove them from the holders, substantially as set forth.

2. The combination with the revolving cone-carrier having a series of sockets or chambers, 110 of the cone releasing bar adapted to enter said sockets at their inner end, and supported at the axis of the carrier, and means substantially as described for causing it to move outward into said sockets, substantially as set forth.

3. In a machine for making paper cones, the combination of the intermittently rotating cone-carrier, the means for intermittently holding said carrier stationary, for the withdrawal of the cones of the continuously revolving shaft B , the gearing loosely connected to said shaft and interposed between it and said carrier and the friction disk rigidly connected to said shaft and adapted to engage with said gearing, substantially as 125 set forth.

4. In a machine for making paper cones, the combination of the intermittently rotating cone carrier, the means for intermittently holding said carrier stationary, the hollow shaft C' , the gearing which drives said shaft C' , the stationary shaft B^6 , and the cone discharging arm or bar, supported on said shaft B^6 , substantially as set forth.

5. The combination with the rotating conical mandrel having a free end, of a carrier or receptacle having a chamber whose walls engage with the cone as it escapes from the mandrel, said mandrel and carrier being arranged whereby one can move longitudinally relative to the other, and a pull-off device arranged at one side of the carrier for removing the cone from the mandrel. 70
10. 6. In a machine for making paper cones, the combination with the rotating conical mandrel having means for positively engaging with a paper blank while it is being wrapped, of a carrier or receptacle having a chamber whose walls will engage with the cone as it escapes from the mandrel, said mandrel and receptacle being arranged substantially as set forth whereby one can move relatively to the other to bring the cone on the mandrel within the chamber in the carrier, and means for removing the cone from the mandrel while it is within such chamber, substantially as set forth. 75
15. 7. The combination with the cone-carrier, and the continuously revolving shaft B, of the catch engaging with the carrier, the catch releasing device moved by said shaft B, the gearing interposed between said shaft and the carrier, and the automatic friction clutch between said shaft and said gearing, substantially as set forth. 80
20. 8. The combination of the mandrel having the rotating paper wrapping cone shaped free end, the pressure plate, against which the paper is pressed while it is rotating and wrapping the paper, the heater below and adjacent to the mandrel and adapted to soften the adhesive at the time the mandrel is wrapping the paper against said plate, a pull-off for the cone and means for moving the mandrel from the heater to the pull-off, substantially as set forth. 85
25. 9. The combination with the rotary conical mandrel of the pressure device opposed to the mandrel, the spring-actuated pull-off movable toward and from the axis of the mandrel, and means for reciprocating the mandrel, substantially as set forth. 90
30. 10. The combination with the cone former, the pressure plate, by the side of the former, the pull-off, normally situated at or outside of the end of the former, and means for reciprocating the former across the space between the pressure plate to the pull-off, substantially as described. 95
35. 11. The combination with the revolving and longitudinally reciprocating mandrel having paper engaging devices to hold it while the mandrel is rotating to wrap the paper of the intermittently movable cone-carrier or receiver in front of the mandrel, and the automatic take off adjacent to the receiver, substantially as set forth. 100
40. 12. The combination of the cone former and the spring actuated pull-off, normally at or outside of the end of the former, and of which parts one is movable relatively to the other 105
- whereby the pull-off can be intermittently situated behind the cone on the former after it has been formed, substantially as set forth. 70
45. 13. The combination with a rotary mandrel having a longitudinal groove, of a finger or bar in the forward part of said groove, and having its active edge extended longitudinally along said groove and the spring for moving said finger secured to the mandrel by a fastening device situated in the inner end of the said groove, substantially as set forth. 75
50. 14. The combination with the conical mandrel having a longitudinal groove, the gripping-finger in the said groove, and the spring for actuating the finger, whereby the paper is held positively on the mandrel when rotating under external pressure of the non-rotating concave vibrating pressure plate at the side of the said mandrel, substantially as set forth. 80
55. 15. The combination of the mandrel having a cone at the end and a groove formed with the smaller part as at h^2 , and the enlarged part as at h' , at the inner end, the gripping-finger adapted to substantially fill the said smaller outer part of the groove and the spring for said finger secured in the said enlarged inner part of the groove, substantially as set forth. 85
60. 16. The combination with the intermittently rotating mandrel H, and the continuously rotating shaft B, of the wheel J, loose on a shaft B, the friction connection between them, cam K, carried by said shaft, the stop for wheel J, adapted to be moved by said cam K, substantially as described. 90
65. 17. The combination with the intermittently revolving mandrel H, and a continuously revolving shaft B, of the wheel J^3 , the wheel J, loose on the shaft, a projection carried by said wheel J^3 , a stop to engage with said projection, a cam carried by said shaft B, to move said stop in one direction and a spring to move it in the other direction, substantially as set forth. 95
70. 18. The combination with the intermittently revolving mandrel adapted to slide longitudinally, of the shaft A, shaft B, the two wheels E, J, mounted independently of each other on shaft B, the reciprocating mechanism actuated by wheel E, and connected to the mandrel to move it longitudinally, the gearing connecting wheel J with the mandrel, and the gearing connecting shaft A with wheel E and wheel J, substantially as set forth. 100
75. 19. The combination with the intermittently revolving mandrel adapted to move longitudinally, of the shaft B, the shaft A, the two wheels E, J, supported on said shaft B, the wheel J intermittently actuated by the shaft B, the reciprocating mechanism connecting wheel E to the mandrel to slide the latter longitudinally, the gearing connecting wheel J to the mandrel, and an intermittently acting stop to arrest said gearing, substantially as set forth. 105
80. 20. The combination with the rotatory and

longitudinally reciprocating mandrel, the blank feeder, the air exhaust mechanism, and the valve to regulate the exhaust, of the shaft A, the shaft B, the gearing which connects said shafts, the wheel E, the cam N connected to wheel E, for actuating said valve, and the cam E' for sliding the mandrel, substantially as set forth.

21. The combination of a rotatory and intermittently sliding mandrel and a reciprocating blank-feeder, the air exhaust mechanism, the shaft B, the wheel E having a cam N for intermittently connecting the air ex-

haust and a cam E', the reciprocating bars interposed between said cam E' and the reciprocating blank feeder, and the reciprocating bars between said cam and the mandrel to slide it longitudinally, substantially as set forth.

In testimony whereof I affix my signature 20 in presence of two witnesses.

JOHN J. BORDMAN.
